UNITED STATES PATENT OFFICE.

WILLIAM C. BRYANT, OF COLUMBUS, OHIO.

SHEARS.

1,330,515.

Specification of Letters Patent.

Patented Feb. 10, 1920.

Application filed April 11, 1919. Serial No. 289,222.

To all whom it may concern:

Be it known that I, WILLIAM C. BRYANT, a citizen of the United States, residing at Columbus, in the county of Franklin and

5 State of Ohio, have invented certain new and useful Improvements in Shears, of which the following is a specification.

This invention relates to shears, scissors and analogous severing instruments, and has 10 particular reference to a simple and useful tool designed particularly for use by wall decorators in order that the latter may accurately and easily trim off and match the selvage or overlapping edges of wall canvas, 15 or other materials applied to a wall surface by means of an adhesive while the same are in position upon the wall.

In the art of wall decorating sheet canvas of certain widths and of a specially prepared nature is often placed over a plastered wall for the purpose of finishing the latter and so that cracks or crevices which invariably appear in plastered walls will be concealed from exterior view, this canvas 25 surfacing also provides an excellent basis for the reception of the usual wall paper. In hanging the canvas sheets the adjacent edges thereof are permitted to overlap so that by vertically severing the same the 30 edges of the sheeting will be longitudinally alined in a perfectly flush and smooth manner and all selvage projections therein eliminated, thus permitting the meeting edges of said sheeting to be evenly and neatly 35 matched.

Hitherto, to effect the cutting of the selvage edges, it has been customary to merely employ a sharp pointed and bladed tool which is guided in its cutting action by 40 means of a rule or other straight edge. This tool, however, has been found to be defective in that considerable difficulty is encountered in accurately guiding the same during its cutting operations, its pointed extremity cutting into the plastered wall and thereby scarring the latter, its general awkwardness in use, and in the necessity of constantly resharpening the same.

Therefore, it is the object of the present 45 invention to provide an instrument capable of being employed in the above capacity and which will be convenient to employ and

manipulate, easy to guide and control during its cutting operations and having other features therein particularly adapted to the 55 class of work specified.

Another object of the invention resides in a pair of shears wherein is provided a stationary and a movable blade, which blades are pivotally united and are formed to 60 terminate rearwardly in offset angularly disposed manipulating portions, and the forward end of the stationary blade being provided with an integral penetrating projection of peculiar configuration and utility, 65 the same serving to facilitate the insertion of the shears into cutting relation with material to be severed and being also provided with an inserting point which is outside of the resting plane of the stationary blade, so 70 that the point can not catch into the plaster as the shears are advanced along a wall.

With these and other objects in view, as will appear as the description proceeds, the invention accordingly consists in the novel 75 features of construction, combination of elements and arrangement of parts hereinafter fully described and having the scope thereof indicated in the appended claims.

In the accompanying drawing, forming a 80 part of this specification, and in which similar characters of reference denote like and corresponding parts:

Figure 1 is a side elevation of a pair of shears constructed in accordance with the 85 principles of the invention,

Fig. 2 is a top plan view thereof,

Fig. 3 is a fragmentary perspective view of the forward end of the stationary blade,

Fig. 4 is a transverse sectional view taken 90 along the line 4—4 of Fig. 1,

Fig. 5 is a fragmentary side elevation of the meeting edges of canvas sheeting employed in finishing a plastered wall, and

Fig. 6 is a horizontal sectional view taken 95 through the sheeting after the overlapping edges thereof have been cut by the shears.

Referring more particularly to the details of the invention, use is made of a pair of shears A which, in its preferred form, consists of a substantially stationary blade 1 and a movable blade 2, the latter being provided with a fixed head stud 3 which is disposed to operate in the rounded end of a

slot 4 formed in the blade 1. By virtue of this construction said blades may be moved relatively and, if necessary, the same may be disconnected to facilitate the sharpening 5 of their edges. In this instance, said blades are formed with angularly offset manipulating portions 5 and which include finger loops 6, by means of which the shears may be conveniently grasped and operated. Owing 10 to the angular relation of the manipulating portions 5, the shears may be conveniently guided during their cutting movements, as the blade 1 may be maintained in close engagement with a wall or other plane 15 surface while the blade 2 may be oscillated to effect cutting movements. Thus the oscillation of the blade 2 may be accomplished without raising the blade 1 from engagement with said wall owing to the fact that 20 its finger loop 6 will be provided with ample room for oscillation between the finger loop of the stationary blade and the limitations imposed by said wall. This construction of the manipulating portions of the shears renders 25 the latter adaptable for ceiling work as well as for the vertical side walls of a room.

The particular feature of the present invention resides in forming the stationary 30 blade 1 with an integral penetrating projection 7, so as to facilitate the insertion of the shears into cutting coöperation with materials to be severed. To this end the projection 7 consists of a flat upper surface 8 35 which in plan is in the shape of an arrow head, being provided with a forward point 9 and a substantially widened rear portion 10, the portions of the projection below the surface 8 being curved and formed to converge 40 into the body of the blade 1, as indicated by the numeral 11. By thus curving the projection 7 along its under face, its point 9 is located outside of the resting or operating plane of the blade 1, so that the 45 advancing of the latter across a plastered wall will not be attended by the digging in of the point 9 into said wall, but on the contrary said point will be maintained in spaced relation with respect to said wall. The 50 curved part 11 also acts as a fulcrum when the projection 7 is being initially inserted into materials to be cut and serves to facilitate this operation. The widened rear portions 10 of the projection 7 serves to enlarge 55 the opening formed thereby so that the blades 1 and 2 will encounter no difficulty in being brought into cutting relation with the material.

In use, the shears A are particularly 60 adaptable for service in cutting the selvage edges of sheets of wall canvas 12, such as are shown in Figs. 5 and 6 of the drawings. These canvas sheets are preferably placed upon a wall in the manner illustrated in

Fig. 5 so that the edges 13 thereof will overlap. Then in order to eliminate the overlapping edges and to perfectly match the remaining edges of the sheets, use is made 70 of the shears A. The projection 7 of the latter is forced into the overlap 13 at any desired point throughout their length, and it will be seen that through the provision of the projection 7, the insertion of the shears may be readily accomplished. Then, by holding the blade 1 in engagement with the 75 wall 14 the shears may be guided during their cutting operation and that owing to the angularity of their manipulating portions ample room will be provided to actuate the movable blade. In fact, if the blades 1 80 and 2 are well sharpened it will not be necessary to lock the blades, as the latter may be held stationary by the operator and the material severed by simply forcing the blades therethrough. Thus owing to the overlapping 85 relation of the edges 13 when the cutting operation is performed neatness will be obtained in matching the adjacent edges of the sheeting after the overlapping portions have been removed, and the relation established 90 wherein divisions or openings between the sheetings eliminated, thus permitting the materials to evenly mate together or to unite in a uniform and even manner. While a specific use for the shears has been set forth, 95 it is obvious that the same may be also applied to many other different uses such for example, as the trimming of oil cloth, enamelled paper, for the separation of bandages in hospital work and many other different 100 fields of utility.

What I claim is:

1. A pair of shears comprising a substantially stationary and a movable blade, angularly offset finger loops formed with said 105 blades and a substantially arrow head shaped projection formed upon the forward end of the stationary blade and serving to facilitate the insertion of the latter into material to be operated upon.

2. A pair of shears comprising a substantially stationary and a movable blade, said blades being pivotally united and formed to terminate rearwardly in angularly offset manipulating portions, and a substantially 115 arrow head shaped penetrating projection formed upon the forward extremity of one of said blades.

3. A pair of shears comprising a substantially stationary and a movable blade, said 120 blades being pivotally united and formed to terminate rearwardly in angularly offset finger loops, and a projection integrally formed upon the forward end of said stationary blade to facilitate the insertion of 125 the latter into material to be cut, and the point of said projection being outside of the resting plane of the stationary blade.

4. A pair of shears comprising a stationary and a movable blade pivotally united, a penetrating projection integrally formed upon the forward extremity of said stationary blade, and said projection being formed to embody an upper flat surface of arrow head formation, said surface terminating forwardly in a point and the under portions thereof being curved to maintain said point in a plane of utility above that of the resting plane of the stationary blade.
- 5 In testimony whereof I affix my signature.

WILLIAM C. BRYANT.
